[57] CLAIM

I claim the ornamental design for a medical measuring module used to accumulate patient data, as shown and described.

DESCRIPTION

FIG. 1 is a top perspective view of a medical measuring module used to accumulate patient data showing my new design;

FIG. 2 is a bottom perspective view of a medical measuring module used to accumulate patient data showing my new design; and,

FIG. 3 is a rear perspective view of a medical measuring module used to accumulate patient data showing my new design.

It is understood that the undisclosed left side of the claimed article is substantially plain and unornamented.
